(57) **CLAIM**

The ornamental design for a small cell for mounting on a light pole, as shown and described.

DESCRIPTION

FIG. 1 is a perspective view of a small cell for mounting on a light pole showing a first embodiment of our new design. FIG. 2 is a top plan view thereof.

FIG. 3 is a bottom plan view thereof.

FIG. 4 is an enlarged scale partial cross-sectional view thereof, taken along line 4-4 of FIG. 3.

FIG. 5 is a front elevational view thereof.

FIG. 6 is a rear elevational view thereof.

FIG. 7 is a left side elevational view thereof.

FIG. 8 is a right side elevational view thereof.

FIG. 9 is a perspective view of a small cell for mounting on a light pole showing a second embodiment of our new design.

FIG. 10 is a top plan view thereof.

FIG. 11 is a bottom plan view thereof.

FIG. 12 is an enlarged scale partial cross-sectional view thereof, taken along line 12-12 of FIG. 11.

FIG. 13 is a front elevational view thereof.

FIG. 14 is a rear elevational view thereof.

FIG. 15 is a left side elevational view thereof; and,

FIG. 16 is a right side elevational view thereof.

The dot-dash broken lines in FIGS. 3 and 11 define the boundary of the claim, which extends to the boundary but does not include the boundary; while all other broken lines depict portions of the small cell for mounting on a light pole that form no part of the claimed design.

Shading lines shown in the drawings are intended to represent the approximate three-dimensional contour of the design and are not intended to indicate surface decoration.
